MOTORIZED UNIT FOR OPERATING MOTION DISPLAYS

Milton S. Dunkelberger, Dayton, Ohio, assignor to The American Display Company, Dayton, Ohio, a corporation of Ohio

Application February 8, 1937, Serial No. 124,779

5 Claims. (Cl. 74—42)

This invention relates to new and useful improvements in motorized units for operating motion displays.

It is one of the principal objects of my invention to provide a compact, easily assembled and efficient motorized unit for operating window displays or other mechanisms where various numbers and kinds of motion may be desired.

It is another object of my invention to provide a motor-powered unit that may be easily attached to the back of a motion display to provide, with very simple and easy changes, various types of movement such as revolving, rocking, arm, index and cam motions. The index and cam motions are obtained by simple and easy attachments to the motor unit which is also adapted to provide all of the various motions at four different speeds in forward and reverse.

My invention provides, instead of solid shafts, hollow shafts or tubes, preferably two that receive sliding attaching members with locking wing nuts. For example, the hollow drive shaft carries the large gear and eccentric to produce all of the revolving motions. The other hollow shaft, which is the rocker shaft, carries the quick change rocker arm and free wheel, and produces all the motions except the revolving ones.

It is another object of my invention to provide quick change means on the rocker arm for obtaining various length strokes of the eccentric connecting rod.

A further object of my invention is to provide quickly detachable side plates for disassembling the unit.

Other important and incidental objects will be brought out in the following specification and particularly set forth in the subjoined claims.

In the accompanying drawings Figure 1 is a rear end view of my motor-powered display-operating unit. Figure 2 is a view of the back side of that unit. Figure 3 is a sectional view taken through the unit on the line 3—3 of Figure 2, showing the hollow rocker shaft and attachments. Figure 4 is a sectional view taken through the unit on the line 4—4 of Figure 2, showing the hollow drive shaft and connections. Figure 5 is an enlarged view of the back side of the unit, showing a Geneva gear attached to the rocker shaft and an operating disc mounted on the drive shaft driven at low speed. Figure 6 is an end view of the two-step pulleys, showing their arrangement when the rocker shaft pulley is driven at high speed by the drive shaft pulley. And Figure 7 is a perspective view of the bracket

for attaching the motor unit to a motion display.

Referring to the accompanying drawings for a detailed description of the form of embodiment of my invention illustrated in the accompanying drawings, the numeral 1 designates a U-shaped frame to the bottom of which there is secured by screws 2, 2 a U-shaped bracket plate 3. Fitted in holes in the ends of the latter are bearings 4, 4 for a worm shaft 5 to which a worm 6 is secured.

Removably attached to the front end of the worm shaft 5 is a two-step pulley 6a. This pulley may be easily reversed on the shaft to obtain different speeds for that shaft from a two-step pulley 7 on a drive shaft 8, through a flexible belt 9.

The pulley 6a may be firmly held in either one of its opposite positions on the worm shaft 5 by a wing nut 10 applied to its threaded outer end. The reversibility of this pulley permits it to be driven at four different speeds by the motor pulley 7.

As in the present instance, the drive shaft 8 may be the armature shaft of an electric motor 11 that is suspended from the bottom of the frame 1 by a bracket 12. The upper horizontal portion of the latter is secured to the bottom of the frame by the screws 2, 2. The vertical portion of the bracket is forked for attachment by studs 13 and nuts 14 to the motor 11 which may therefore be easily changed from an A. C. to a D. C. type.

Formed in the top edges of the sides of the frame 1 are oppositely disposed front bearing slots and oppositely disposed rear bearing slots. Removably supported in the front bearing slots are grooved bearings 15, 15 for a hollow drive shaft 16. Grooved bearings 17, 17 are removably fitted in the rear bearing slots to support a hollow rocker shaft 18. Retaining members 19, 19 are removably secured by screws 20 to the top portions of the side plates of the frame, over the grooved bearings 15 and 17, to firmly hold them in the bottoms of their respective bearing slots in the sides of the frame. By removing the screws 20 and the retaining members 19, the hollow shafts 16 and 18 and their attachments may be bodily removed from the frame and easily reinserted therein.

Meshing with the worm 6 is a worm gear 21 fast on the hollow drive shaft 16 below a bowed cover plate 22 removably secured to the sides of the frame 1. Attached to the end of the hub 23 of the gear 21 by a rivet 24 are two disc flanges

25, 25 secured by rivets 26, 26 to an eccentric 27. Surrounding the latter is a follower 28 that has a rearwardly projecting rod portion 29 which is pivotally connected by a pin 30 to a slideable member 31. This member has formed in its lower end an elongated slot 32 which is longitudinally slideable over a sleeve 33 that is freely mounted on the rocker shaft 18, and along a rocker arm 34 which is secured to said sleeve against a shoulder 35 thereon.

In the upper portion of the slideable member 31 there is an elongated slot 36 through which a spring-pressed guide pin 37 carried by the rocker arm projects. The member 31 is longitudinally movable along the rocker arm 34 to adjust the throw of the eccentric connecting rod 29, and is held in an adjusted position by a quick change knob 38 carried by the slideable member and having a pin end which is insertible in one of a series of holes 39 in the upper portion of the rocker arm. In this instance three holes 39 are provided in the rocker arm, the top hole for short motions thereof, the center hole for medium rocker motions and the lower hole for long rocker motions.

For the purpose of easily and quickly attaching the operating unit just described to a display which is to be actuated by it, I provide a sleeve 40 which projects transversely through the central portion of the sides of the frame 1.

The sleeve 40 is adapted to receive from either direction and support, a shaft 41 to one end of which a winged U-shaped bracket 42 is secured and whose other end is threaded to receive a wing nut 43. (See Figure 7.) The central U-shaped portion of the bracket has side wings 44, 44 formed with holes that receive wing nut attaching elements 45 for securing the bracket to a motion display. Below the rod 41 an alining stud 46 projects outwardly from the central part of the bracket for entrance in a hole 47 in the side of the frame to which the bracket is attached. (See Figures 2 and 7.)

The bracket and sleeve construction just described permits the display to be attached to opposite sides of the motor unit. To secure it to one side of the latter, the bracket shaft 41 is passed through the sleeve 40 on that side and the wing nut 43 tightened; and to attach it to the other side of the motor unit, for a reverse motion of the display, the shaft 41 is inserted in the opposite end of the sleeve. Thus, the motion display used with my motor unit may be driven by the latter in either a clockwise or anti-clockwise direction, depending upon the side of that unit to which the display is attached by the reversible bracket.

For the purpose of imparting a rocking movement to any part of the display, the shaft 18 is oscillated by the rocker arm 34 through the following means. Attached to a collar 48 fixedly secured to the hollow shaft 18 between the rocker arm sleeve 33 and the opposite side of the frame 1, is a disc 49 which carries a set screw 50 that is adapted to enter a tapped hole 51 in the rocker arm 34.

When the disc 49 is thus connected to the rocker arm, the latter will oscillate the hollow shaft 18 to rock, in turn, a display part (not shown) connected to a bracket 58 whose rod 52 is inserted in the shaft and locked thereto by lugs 53, 53 which engage in notches in one end of the shaft, and by a wing nut 54 applied to the opposite end of the rod.

If it is desired to impart an intermittent rotary

motion to a motion display, the set screw 50 is withdrawn from the hole 51 in the rocker arm 34 so that the hollow shaft 18 may rotate free of the latter. In the present instance, a Geneva gear 55 is applied to that shaft for intermittent engagement by a pin 56 on the face of a driving wheel 57 secured to the drive shaft 16. When the latter is rotated by the motor 11 through the drive mechanism heretofore described, the notched gear 55 will be intermittently rotated with the hollow shaft 18, which is now free to rotate independently of the rocker arm 34. Revolving motions may also be imparted to a motion display by locking the attaching means directly to the hollow drive shaft 16.

The speed at which the drive shaft 16 is driven will be dependent upon the position of the two step pulley on the worm shaft 5 and the pulley parts which the belt 9 encircles.

In Figure 5 the pulley and belt arrangement is such that the shaft 5 will be driven at a low speed; in Figure 6 it is driven at a high speed, whereas in Figure 2 the pulley 6^a has a reverse position on the shaft 5 to drive the shaft 5 at intermediate speed.

It will now be seen that the long hollow shafts 16 and 18 make possible the attachment of parts by sliding the rods or shafts of the attaching means through the shafts and locking them thereon by wing nuts. No tools are therefore necessary to lock any parts of a motion display to these hollow shafts of the operating unit.

Having described my invention, I claim:

1. In a device of the type described for imparting motion to a movable member, a support, a hollow shaft journaled in said support, a rocker arm loosely mounted on said shaft, means for attaching said rocker arm to the shaft, means for imparting a rocking movement to said arm comprising driving means, eccentric means associated therewith, and an operating connection between said driving means and said arm, and an element extending into the hollow shaft for attaching the movable member thereto for a rocking movement thereby, said hollow shaft and said element being provided with cooperating means for detachably securing the same together.

2. In a device of the type described, a frame, a pair of shafts journaled in said frame, means carried by said frame for rotating one of said shafts, an eccentric secured to the rotated shaft, a rocker arm loosely secured to the second shaft, a rod connecting the eccentric to said arm to rock the latter, a disc fixedly secured to the second shaft, and means for removably connecting said disc to the rocker arm to oscillate the second shaft.

3. In a device of the type described, a support, a pair of alined shafts journaled in said support, means for rotating one of said shafts, a disc fixedly secured to the second shaft, an eccentric secured to the first shaft, a follower associated with the eccentric, and means for removably connecting said disc and said follower to oscillate the second shaft.

4. As a new article of manufacture, an operating unit for motion displays, comprising a support, a plurality of parallel hollow shafts for operating movable parts of a motion display, said shafts being journaled in said support and each shaft having an operating portion accessible at opposite sides of said support for connection therat with a movable part of a motion display, each of said shafts also having locking means adjacent its ends, means for imparting movement

to one of said shafts, and an auxiliary shaft insertable in either hollow shaft from either end thereof, said auxiliary shaft having means cooperable with the aforesaid locking means at one end of one of said hollow shafts for fixedly securing said auxiliary shaft to either of said hollow shafts, whereby said auxiliary shaft is interchangeably associable with either hollow shaft for rotation relative to, or for fixed connection with, the hollow shaft in which it is inserted.

5. An operating unit for motion displays, comprising a support, a plurality of parallel hollow shafts for operating movable parts of a motion display, said shafts being journaled in said support, and each shaft having an operating portion

10
15

accessible at opposite sides of said support for connection therewith a movable part of a motion display, means for imparting movement to one of said shafts, and an auxiliary shaft insertable in either hollow shaft from either end thereof, said hollow shafts and said auxiliary shaft being provided with cooperating means for detachably securing the same together, whereby said auxiliary shaft is interchangeably associable with either hollow shaft for rotation relative to the hollow shaft in which it is inserted, or alternatively, for fixed connection of the auxiliary shaft with the hollow shaft in which it is inserted.
